(57) **CLAIM**

The ornamental design for a first aid case, as shown and described.

DESCRIPTION

FIG. 1 is a perspective view of the first aid case, according to the present invention;

FIG. 2 is a top view of the first aid case, according to the present invention;

FIG. 3 is a bottom view of the first aid case, according to the present invention;

FIG. 4 is a side view of the first aid case, according to the present invention;

FIG. 5 is an end view of the first aid case, according to the present invention;

FIG. 6 is a perspective view of the first aid case, according to the present invention, with the lid halves open;

FIG. 7 is a cross-sectional view of the first aid case according to the present invention, shown along line 7—7 of FIG. 4;

FIG. 8 is a cross-sectional view of the first aid case according to the present invention, shown along line 8—8 of FIG. 4;

FIG. 9 is a cross-sectional view of the first aid case according to the present invention, shown along line 9—9 of FIG. 9; and,

FIG. 10 is a cross-sectional view of the first aid case according to the present invention, shown along line 10—10 of FIG. 4.
